US00D917396S

(12) **United States Design Patent** (10) **Patent No.:** **US D917,396 S**
(45) **Date of Patent:** **** Apr. 27, 2021**

(54) **CONNECTION HOUSING**

(71) Applicant: **Alexander Binzel Schweißtechnik, Buseck (DE)**

(72) Inventor: **Steffen Assmann, Freital (DE)**

(73) Assignee: **Alexander Binzel Schweißtechnik GmbH & Co. KG, Buseck (DE)**

(**) Term: **15 Years**

(21) Appl. No.: **29/686,239**

(22) Filed: **Apr. 3, 2019**

Related U.S. Application Data

(62) Division of application No. 29/557,871, filed on Mar. 14, 2016, now Pat. No. Des. 849,808.

(51) **LOC (13) Cl. 13-03**

(52) **U.S. Cl.**

USPC D13/133

(58) **Field of Classification Search**

USPC D4/138; D8/107; D13/133, 146, 149, D13/154; D15/139, 144, 199; D23/213, D23/259; D24/129, 133

CPC .. G02B 6/3893; G02B 6/3817; G02B 6/3825; H01R 31/06

See application file for complete search history.

CLAIM

The ornamental design for a connection housing, as shown and described.

DESCRIPTION

FIG. 1 is a bottom, front, left side perspective view of a connection housing, showing my new design;

FIG. 2 is a bottom, front, right side perspective view of the connection housing of FIG. 1;

FIG. 3 is a front elevational view of the connection housing of FIG. 1;

FIG. 4 is a top plan view of the connection housing of FIG. 1;

FIG. 5 is a rear elevational view of the connection housing of FIG. 1;

FIG. 6 is a left side elevational view of the connection housing of FIG. 1;

FIG. 7 is a right side elevational view of the connection housing of FIG. 1; and,

FIG. 8 is a bottom plan view of the connection housing of FIG. 1.

The broken lines shown in the drawings depict portions of the article and form no part of the claimed design.

1 Claim, 4 Drawing Sheets
